UNITED STATES PATENT OFFICE.

HARRY P. FAIRCHILD, OF NEW YORK, N. Y.

DESIGN FOR A HANDLE FOR CUTLERY.

SPECIFICATION forming part of Design No. 21,413, dated March 22, 1892.

Application filed February 16, 1892. Serial No. 421,763. Term of patent 3½ years.

To all whom it may concern:

Be it known that I, HARRY P. FAIRCHILD, a citizen of the United States, residing at New York, in the county of New York and State of New York, have invented a certain new Design for a Handle for Cutlery, &c., of which the following is a specification.

My invention consists of a new design for a handle for button-hooks, files, and cutlery, or any similar article requiring a handle.

The design is best described by the accompanying drawing, which shows the design in full as applied to a handle, the drawing show-

ing a face view of one side of the handle, having the design formed thereon.

15

The same design is preferably applied to both sides of the handle.

What I claim as my invention is—

The design for a handle, as herein shown and described.

20

In witness whereof I hereunto set my hand in the presence of two witnesses.

HARRY P. FAIRCHILD.

Witnesses:

L. FRED HURD,
SAMUEL H. SMITH.
